UNITED STATES PATENT OFFICE.

HENRY B. CLARKE, OF OAK PARK, ILLINOIS.

TROLLEY-RETRIEVING DEVICE.

SPECIFICATION forming part of Letters Patent No. 791,750, dated June 6, 1905.

Application filed September 3, 1904. Serial No. 223,284.

To all whom it may concern:

Be it known that I, HENRY B. CLARKE, of Oak Park, in the county of Cook and State of Illinois, have invented certain new and useful 5 Improvements in Trolley-Retrieving Devices, of which the following is a specification.

This invention relates to trolley-retrieving devices, and more particularly to a device adapted to stop the upward movement of a 10 trolley-pole which has accidentally jumped from the trolley-wire and to automatically pull it to a position below the trolley-wire and hold it there to prevent it from becoming engaged with the cross-wires and overhead supports, with the consequent damage thereto.

Among the salient objects of the invention are to provide a device of the character referred to adapted to be attached to and operate upon the base of a trolley-pole, thereby 20 locating the device upon the roof of the car in an out-of-the-way place; to provide a device adapted to utilize an auxiliary power, such as air-pressure, generated by the driving mechanism of the car, for the purpose of catching a trolley-pole and returning it to a position free from the cross-wires and overhead supports; to provide in such a device a valve mechanism connected with and operated by the trolley-pole, whereby the abnormal movement 30 of the latter operates to automatically put into operation said auxiliary power for the purpose referred to, and, in general, to provide a simple, durable, and practical device of the character referred to.

The invention will be readily understood from the following description of one embodiment thereof when considered with the accompanying drawings, illustrating same, and in which—

Figure 1 is a side elevation of one form of device attached to the lower end of a trolley-pole with parts broken away and parts shown in section. Fig. 2 is an enlarged sectional detail. Fig. 3 is a side elevation of the device 45 attached to a trolley-pole in its normal position, and Fig. 4 is a similar view with the trolley-pole in the position in which it is held after the device has operated.

Referring to the drawings, 1 designates a

trolley-pole pivotally supported at 2 upon a 50 standard 3, mounted upon the top of a car or other support. The lower end of said trolley-pole projects beyond the pivotal point, as at 4, and has attached thereto a rod member 5, which extends back and is secured to a collar 55 6, slidably mounted upon a supporting-bar 7, secured to a block member 8 upon the standard 3. A coiled expansion-spring 9, mounted upon the supporting-bar 7 between the collar 6 and the block member 8, tends to move said 60 collar outwardly upon said bar 7, thereby holding the upper end of the trolley-pole in yielding engagement with the trolley-wire.

10 designates a bracket-like member upon the trolley-pole adjacent the standard 3 and 65 having a slightly-curved bearing-surface 11, over which rides a brake-shoe 12, pivotally supported upon an arm 13 and adapted to be brought into frictional engagement with said bearing-surface 11 in a manner and for a purpose hereinafter referred to. The upper end of said arm 13 is pivoted to the trolley-pole, as at 14.

15 designates a cylinder or casing pivotally supported at one end upon a member 16, 75 mounted upon the outer end of the supporting-bar 7 and provided therein with fluid-chambers 17 and 18. Mounted to reciprocate within the chamber 17 is a fluid-actuated piston 19, and in the chamber 18 is a valve-piston 80 (designated as a whole 20,) said piston and valve-piston being connected, respectively, with the piston-rods 21 and 22, working through the stuffing-boxes 23 and 24 and pivotally connected, respectively, with the trolley-pole 1, as at 25, and with the brake-shoe 12 and arm 13, as at 26.

The partition-wall 27 between the chambers 17 and 18 is provided with a plurality of communicating ports 28, hereinafter referred 90 to, while 15' designates a vent opening from the chamber 17 in the rear of the piston 19.

The valve-piston 20 in the chamber 18 is of a hollow cylindrical form, closed at one end. The end of the piston-rod 22 passes slidably 95 through said end closure, as indicated at 20', Fig. 2, and is rigidly connected with the end of a similar but smaller hollow cylindrical

member 29, movably mounted within the valve-piston head 20. A spring 30, mounted upon the end of the piston-rod 22 between the end of the inner cylindrical member 29 and the end closure of the piston-head 20, yieldingly retains the members in the position shown in Fig. 2, whereby a port 31 in the wall of the cylindrical member 29 is held normally out of register with a similar port 32 in the wall of the member 20, said port 32 being in communication at all times with one or another of the ports 28 in the partition-wall 27 and the other ports 28 being closed against communication between the chambers 17 and 18 by the cylindrical member 20. A collar 33, rigidly mounted upon the piston-rod 22, limits the movement of the cylindrical member 29 within the piston-head 20. The brake-shoe 12 is normally held out of engagement with the bearing-surface 11 on the bracket member 10 by means of a coiled expansion-spring 34, mounted upon the piston-rod 22 and bearing at one end against the stuffing-box 24 of the cylinder 15 and at the other end against a collar 35, mounted upon said piston-rod adjacent said brake-shoe.

36 designates as a whole a pipe for supplying the actuating fluid, such as air under pressure, to the cylinder 15, said pipe passing upwardly through the standard in the present instance, as indicated at 37, and from said standard into the outer end of the chamber 18, as at 38. A branch pipe of smaller diameter and designated 39 leads from the main pipe 36 into the opposite end of the chamber 18, as indicated at 40, whereby the pressure in said chamber 18 at one side of the valve-piston head equals or balances that at the other side of said piston-head.

40 In order to provide for certain bodily movement of the cylinder 15 upon its pivotal support, a flexible section 41, composed of wire-wrapped hose, is provided and forms a portion of the pipe 36. Flexible joints 42 and 43 are also provided, respectively, in the main pipe 36 and the branch pipe 39.

45 A limit-link 44 is mounted upon the trolley-pole 1 and engages the arm 13 to prevent said arm from being moved outwardly too far under the tension of the spring 22.

50 45 designates a spring-closed vent-cock of any suitable and well-known type mounted upon the cylinder 15 and communicating with the chamber 17 in front of the piston-head 19. 55 This cock is opened by the conductor or other attendant by means of a cord 46 after he has taken the trolley-cord for the purpose of returning the trolley-pole to the wire, said vent-valve being opened sufficiently to permit the 60 air to escape from the cylinder-chamber 17, and thus permit the trolley-pole to move upwardly under the tension of its spring 9 and be replaced upon the wire in the usual manner.

The operation of the device may be briefly

stated as follows: The trolley-pole moves upwardly against the trolley-wire by reason of its spring 9 in the manner described, and when the trolley-pole accidentally jumps from the wire the tension of said spring 9 tends to throw it upwardly into a vertical position and into engagement with the cross-wires and overhead supports, with the consequent damage to the same. Assuming that the trolley-pole has accidentally left the wire and started to move upwardly under the tension of said spring, the movement of the pole carries the piston-rods 21 and 22, the forward movement of the piston-rod 22, however, being momentarily retarded until the brake-shoe 12 engages the bracket 10, whereupon the forward movement of the trolley-pole is transmitted, through the piston-rod 22, to the inner cylindrical member 29, which is carried forward within the piston-head 20 until the port 31 registers with the port 32 and one of the ports 28. Thereupon the air under pressure in the cylinder 29 and the chamber 18 is free to escape into the chamber 17 in front of the piston-head 19, forcing the latter toward the rear end of the chamber 17 and drawing the trolley-pole with it to a position somewhat below the trolley-wire by means of the piston-rod 21, where it is held until released by opening the vent-valve 45 by pulling the cord 46. It is to be understood that the air-pressure in front of the piston-head 20, together with the inertia of the piston member 20, during the initial forward movement of the member 29 is sufficient to overcome the tension of the spring 30 and permit the member 29 to move forwardly sufficiently to bring the port 31 into register with the port 32 for a sufficient time to cause the increased pressure in the chamber 17 in front of the piston-head 19 to carry the latter backwardly enough to pull the trolley-pole to a safe position.

The valve mechanism which controls the inlet to the chamber 17 is connected to the trolley-pole by the piston-rod 22, the brake-shoe 12, and the arm 13. By this construction a lost motion is established between the movement of the trolley-pole and the starting movement of the valve mechanism by reason of the fact that the pole moves forwardly a short distance before the brake-shoe is engaged by the bracket 10, which engagement then pulls forward the valve-mechanism piston 22 in the manner described. After the pressure in the chamber 18 in front of the valve mechanism 20 is overcome and the inertia of the member 20 the spring 34 moves the piston-rod 22 forward sufficiently to release the brake-shoe from frictional engagement with the bracket 10 and the parts assume their normal position, as shown in Fig. 1.

125 While I have herein shown and described a device adapted to use the air generated by the car for its brake mechanism, it is obvious

that the device can be adapted to utilize any actuating fluid and that alterations and modifications in the mechanism can be made without departing from the spirit of the invention, 5 and I do not, therefore, limit the invention to the details of construction and arrangement shown and described except in so far as they are made the subject-matter of specific claims.

I claim—

- 10 1. A retrieving device for trolley - poles, comprising in combination with a trolley-pole, a fluid-chamber, a fluid-actuated piston mounted within said chamber and operatively connected with said trolley-pole, a fluid-supply pipe to said chamber, an automatic valve mechanism controlling the inlet to said chamber, and a lost-motion connection between said valve mechanism and said trolley-pole, for the purpose described. 15
- 20 2. A retrieving device for trolley - poles, comprising in combination with a trolley-pole, a casing provided with primary and secondary fluid - chambers with communicating ports therebetween, a fluid-actuated piston mounted within said primary chamber and operatively connected with said trolley-pole, a valve-piston mounted within said secondary chamber and operatively connected with said trolley-pole, said valve mechanism adapted to control the ports opening into said primary chamber, and a fluid-supply pipe into said secondary chamber, substantially as and for the purpose described. 25
- 30 3. A retrieving device for trolley - poles, comprising in combination with a trolley-pole, a casing provided with primary and secondary fluid-chambers with communication therebetween, a fluid-actuated piston within said primary chamber and operatively connected with 35 said trolley-pole, a valve-piston within said secondary chamber and adapted to control the communication-inlet to said primary chamber, a fluid-supply pipe discharging into said secondary chamber, and a lost-motion connection 40 between said trolley-pole and said valve-piston, whereby an abnormal movement of said trolley-pole actuates said valve-piston to open the communication into said primary chamber, for the purpose described. 45
- 50 4. A retrieving device for trolley - poles, comprising in combination with a trolley-pole, a casing provided with primary and secondary fluid - chambers with communicating ports therebetween, a fluid-actuated piston mounted within said primary chamber and operatively connected with said trolley-pole, a valve-piston mounted within said secondary chamber to control the inlet to said primary chamber, said valve-piston comprising a two-part member 55 with openings therein adapted to be brought into register with each other and with the communicating ports into said primary chamber and being normally held out of register with each other, said valve-piston being connected with said trolley-pole, where- 60
- 65 by an abnormal movement of said trolley-pole moves the openings in said two-part member into register with each other and opens communication between said primary and secondary chambers, and means for supplying an actuating fluid under pressure to said secondary chamber, substantially as and for the purpose described. 70
- 70 5. A retrieving device for trolley - poles, comprising in combination, a fluid-chamber, a fluid-actuated piston within said chamber and connected with said pole, a valve-chamber with communicating ports into said fluid-chamber, a two-part valve member operatively connected with said trolley-pole and controlling said communicating ports, the parts of said member having openings therethrough adapted to be moved into register with each other and with the ports into said fluid-chamber by any abnormal movement of said trolley-pole, and 75 means for supplying actuating fluid under pressure to said valve-chamber. 80
- 80 6. In a trolley-retrieving device, the combination with the trolley-pole, of a casing provided with primary and secondary air-chambers, a piston mounted within said primary chamber and operatively connected and moving with said trolley-pole, a valve-piston within said secondary chamber and controlling the communication between said primary and secondary chambers, said valve-piston being connected by a lost-motion connection with said trolley-pole, whereby the movement of said trolley-pole under abnormal conditions operates to actuate said valve-piston, and a supply-pipe with branch for supplying air under pressure into said secondary air-chamber at each end thereof, substantially as and for the purpose described. 90
- 90 7. In a trolley-retrieving device, the combination with a trolley-pole, of a bracket member upon said pole having a brake bearing-surface, a brake-shoe pivotally mounted upon said trolley-pole and adapted to swing into frictional engagement with said bearing-surface, a casing provided with a primary and a secondary air-chamber and pivotally supported adjacent said trolley-pole, a piston mounted within said primary chamber and operatively connected with said trolley-pole, a piston-valve within said secondary chamber and controlling communicating ports between said primary and secondary chambers, said piston-valve being connected with said brake-shoe and adapted to be operated by the movement 100 of said trolley-pole and brake-shoe, in the manner described, a supply-pipe for delivering air under pressure to said secondary chamber, said supply-pipe being provided with a branch, whereby air is delivered into each end 105 of said chamber, and a vent-cock mounted upon said casing and communicating with said primary chamber, all substantially as and for the purpose described. 110
- 110 8. A trolley-retrieving device, comprising a 115
- 120
- 125
- 130

fluid-chamber, a fluid-actuated piston within said chamber and connected with said trolley, a valve-chamber alongside of said fluid-chamber with communicating ports therebetween,
5 a piston-valve within said valve-chamber controlling said ports, the piston-rod of which is connected with said trolley-pole and positively

moved in either direction by the movement of said pole, and means for supplying actuating fluid under pressure to said valve-chamber.
